UNITED STATES PATENT OFFICE.

GEORGES LABOLLE, OF PARIS, FRANCE.

COOLING INSTALLATION.

Application filed May 31, 1922. Serial No. 565,003.

To all whom it may concern:

Be it known that I, GEORGES LABOLLE, citizen of the French Republic, residing at Paris, Department of the Seine, in France, ⁵ have invented certain new and useful Improvements in or Relating to Cooling Installations, of which the following is a specification.

This invention relates to improvements in ¹⁰ cooling or heating apparatus and the primary object of the same is to provide a system whereby either cold or heat may be supplied to the various apartments of a building.

¹⁵ A further object of the invention is to provide a system of this character combined with ventilating means so that the air in the apartment or apartments may be circulated alone or may be circulated while being ⁵⁵ cooled or heated.

With the foregoing objects outlined and with other objects in view which will appear as the description proceeds, the invention consists in the novel features herein-²⁰ after described in detail, illustrated in the accompanying drawings and more particularly pointed out in the appended claims.

Referring to the drawings:

Figure 1 is a vertical sectional view of ²⁵ an expansion device forming part of my improved system.

Fig. 2 is a top plan view of the same.

Fig. 3 is a side view partly in section of ³⁰ a modified form of the expansion device.

Fig. 4 is an end view of the same.

Fig. 5 is a vertical sectional view of a ³⁵ regulating device forming part of the sys-

tem.

Fig. 6 is a top plan view of the same. ⁴⁰ Fig. 7 is a vertical sectional view of one of the combined temperature exchangers and air circulating devices forming part of the apparatus.

Fig. 8 is a transverse sectional view of the ⁴⁵ same.

Fig. 9 is a side view of one of the tubes forming part of the heat exchanger.

Fig. 9' is a similar view of another form of tube forming part of the heat exchanger.

Fig. 10 is a side view of a combined valve and switch used with the system.

Fig. 11 is a top plan view of the same.

Fig. 12 is a diagrammatic view of the ⁵⁰ entire system.

Referring first to Fig. 12 for the purpose of explaining the direction of travel of the brine used in the cooling system, it is to be noted that brine cooled in the tank 3 is ⁵⁵ pumped up the pipe 5 into the regulating tank 20, which is located at the upper end of the system. From the tank 20 the brine descends by pipe 5' and in its descent may travel through heat exchangers 19. The ⁶⁰ brine pumped into the tank 20 enters the same faster than it may leave the tank and this causes the level of the brine in the tank 20 to rise, and this fluctuation in the level of the brine in the tank 20 is utilized for ⁶⁵ controlling the circuit of the motor of the pump, in a manner hereinafter described.

If heat is to be provided instead of cold, then the water or other medium rises from the boiler 3' through pipe 5 and returns to ⁷⁰ the boiler through the pipe 5'.

The tank 3 is illustrated in Figs. 1 and 2 and it is provided with an automatic refrigerator 4, which cools the brine. The brine is withdrawn from the tank by means ⁷⁵ of the pump 2 which forces the same up the pipe 5, and this pump is driven by an electric motor 1. When the brine travelling up the pipe 5 reaches the tank 20 it travels into the same through a pipe 5² and some of ⁸⁰ the brine accumulates in this tank by passing through the aperture 5³. The nipple 5⁴ is connected to the pipe 5' and it will be noted that the aperture through this nipple is restricted, so that brine entering the tank ⁸⁵ cannot pass out as fast as it enters. Consequently the brine level in the tank 20 will rise and this will cause elevation of the float 8. The float 8 operates a switch (not shown) which controls the motor 1. Therefore when brine rises in the tank 20 to a sufficient height, the motor circuit will be opened and the pump will cease to operate.

In Figs. 3 and 4 the modified form of expansion tank consists of a chamber 20^a from ⁹⁰

- which the brine is discharged by a pipe 21 into the pump 2. This tank also includes an automatic refrigerator 22 or instead of the automatic refrigerator a coil may be arranged in the tank and a cooling fluid may be passed through this coil by way of pipes 24 and 25 for the purpose of cooling the brine in the tank. The brine is returned to the tank by means of the pipe 23. 5
- 10 In these figures the pipe 23' designates an overflow pipe which extends up into the tank 20 as shown at 23''. 26 designates a tap for permitting air to escape from the tank 28 through the valve 27. 10
- 15 As before stated, the brine from tank 20 descends through pipe 5' and this pipe is connected to a number of heat exchangers 19, one of which is shown in detail in Figs. 7 8, 9 and 9'. Said heat exchanger comprises 20 a number of tubular elements 10 and 10' grouped radially and assembled in such manner as to form a circuit for the circulation of the brine. The latter in the example shown enters by the tube or pipe 13 at the 25 top and escapes by the pipe or tube 14 at the bottom. In the arrangement shown by way of example, the heat exchanger is of the horizontal type having pockets 11 at its ends for the collection of the condensate. 30
- 35 In a vertical type of temperature or heat exchanger the condensate are collected at the bottom of the apparatus.
- The parts or elements of the heat exchanger are shown in full lines, but if it be found necessary, the number of these parts may be considerably increased, the additional parts being indicated in dotted lines. 40
- These elements or tubular parts are mounted in a cylindrical metallic casing 15 open for a certain part of its length as at 15', the length of the opening corresponding to the length of the elements through which the brine circulates. The position of the opening 15' relative to the apartment or the like 45 to be cooled or ventilated, is such as indicated for example in Fig. 12. Electrically actuated fans 12, 12 (Fig. 7) are placed near the ends of the opening 15', the function of these fans being to create an increased air pressure and circulation of the air past the elements conveying the brine. 50
- The system includes a combination valve and switch for each heat exchanger, the valve controlling the passage of the brine 55 through the heat exchanger and the switch controlling the operation of the fans 12, and in order to permit this, a structure of the type disclosed in Figs. 10 and 11 is employed. This structure includes a valve casing 17 60 to which brine is admitted by a pipe 17' and from which it is discharged through a pipe 17''. The valve proper has a stem connected to a handle 16 and the manipulation of this handle permits opening and closing of the 65 valve. The handle carries an extension 16' which has a contact adapted to be brought into register with fixed contacts 18. The extension 16' and contacts 18 are arranged in the circuit of the motors which drive the fans 12, so that the handle 16 may control the operation of said fans. Referring to Fig. 11, the position A of the handle corresponds to the closed position of the valve and the positions B, B', C and C' correspond first, to cooling and ventilation 70 with two speeds and the second to ventilation only, with two speeds. 75
- In operation, assuming that the valves of all the heat exchangers are closed, brine will be prevented from passing down the pipe 5' 80 and the pump 2 may continue to operate until the level of the brine of the tank 20 has raised the float 8 and opened the circuit of the motor 1. At this time there will be no circulation of the brine through the system. If now one of the valves of the temperature exchangers is opened, the brine will commence to flow downwardly from the tank 20 through the open heat exchanger and pipe 5' into the tank 3. As soon as the float 8 85 has descended sufficiently the motor circuit will be closed and the pump 2 will then draw brine from the tank 3 and force the same up to the tank 20. In this manner the cold brine finally reaches the heat exchanger 90 which is open and as long as the valve of this heat exchanger remains in open position, the brine level in the tank 20 will rise and fall intermittently and the pump 2 will function intermittently to replace the brine withdrawn from the tank 20. 95
- 100 From the foregoing it is believed that the construction, operation and arrangement of parts may be readily understood, and it is apparent that changes may be made in the construction illustrated without departing from the spirit of the invention as expressed in the claims. 105
- 110 What I claim and desire to secure by Letters-Patent is:
1. A temperature exchanging system including an upper and lower tank, a pipe for conveying a temperature changing medium from the lower tank to the upper tank, a second pipe for conveying the medium from the upper tank to the lower tank, temperature exchangers associated with one of said pipes, a pump for circulating the medium through said pipes, and regulating means associated with one of said tanks for controlling the operation of said pump. 115
  2. A system as claimed in claim 1 in which one of said tanks is provided with means for cooling the interior of the same. 120
  3. A system as claimed in claim 1 including an automatic refrigerator arranged within the lower tank. 125
  4. A system as claimed in claim 1 including an electric motor for driving said pump, said motor being controlled by the con- 130

trolling means arranged in one of said tanks.

5. A system as claimed in claim 1 including a fan associated with one of said heat exchangers, and means for controlling the passage of medium through said heat exchanger and the operation of said pump.

6. A system as claimed in claim 1 including a fan associated with one of said heat

exchangers, and a combined valve and switch associated with the heat exchanger and fan for controlling the same.

In testimony whereof I affix my signature in the presence of two witnesses.

GEORGES LABOLLE.
